[57] **CLAIM**

The ornamental design for a packaging container as shown and described.

DESCRIPTION

FIG. 1 is a top front perspective view of a packaging container showing my new design;
FIG. 2 is a rear elevational view;
FIG. 3 is a top plan view;
FIG. 4 is a side elevational view, the opposite side being a mirror image thereof;
FIG. 5 is a medial sectional view; and
FIG. 6 is a front perspective view in an open position.
